UNITED STATES PATENT OFFICE.

THEODORE O. LOVELAND, OF IOWA CITY, IOWA.

SOUND RECORDING AND REPRODUCING MACHINE.

1,406,046.

Specification of Letters Patent.

Patented Feb. 7, 1922.

Application filed June 10, 1919. Serial No. 303,036.

To all whom it may concern:

Be it known that I, THEODORE O. LOVELAND, a citizen of the United States, residing at Iowa City, county of Johnson, and

5 State of Iowa, have invented certain new and useful Improvements in Sound Recording and Reproducing Machines; and I do hereby declare the following to be a full, clear, and exact description of the invention, 10 such as will enable others skilled in the art to which it appertains to make and use the same.

This invention relates to sound recording and reproducing machines of the cabinet 15 phonograph type which employ, in addition to the usual sound box and tone arm, an amplifying or tone chamber that is in coupled communication with the tone arm through the medium of a sound conveying 20 conduit, commonly termed the throat, and the specific improvement embodied herein more particularly resides in a novel departure as to the structural treatment of the throat itself.

25 Such throats formed wholly of metal have been, and to a minor extent may still be, employed in some machines, but it seems impossible to avoid the resultant metallic tones therefrom, and for the transmission of su- 30 perior tone values it is generally conceded, in this and other musical industries, that wood is the very best material that may be adopted.

35 These hollow throats, therefore, are pref- erably formed with walls of a carefully selected wood, and their interior surfaces, must be of a continuously smooth or unob- structed character as their acoustic proper- 40 ties are of the utmost importance, in the transmission of sound waves as constant values from the sound box to the tone chamber of the machine, to insure a delicately accurate reproduction of the record being translated.

45 It has been observed, however, that in the course of time, regardless of the quality of the seasoned wood or any attempted varnished protection thereof as may have been heretofore practiced, the sound reverberating 50 life and responsive or attuned pitch of the interior surfaces of these wooden walls seem to materially deteriorate, in the sense that they become deadened, as it were, while the walls themselves become slightly warped, 55 separated or otherwise affected, which dis- torts the continuously smooth or uniform evenness requisite for their proper function-

ing, all of which defects are doubtless due largely to an excess or an unequal absorption or distribution of moisture, and also 60 by thermal conditions from variable temperatures.

It is manifest, therefore, that such conditions cause serious alterations, impairment and depreciation of the tone values emitted, 65 and the primary object of the present invention is to overcome the foregoing and other defects, while at the same time promoting maximum efficiency, in a simple and lasting manner as herein provided for, by the pres- 70 ervation of proper pitch and tone qualities, the maintenance of the sound waves as constant values in their passage from the tone arm to the tone chamber, and the perfection generally of the acoustic qualities of 75 the intermediate throat, the utility and novelty of which latter will be so clearly apparent, as incidental to the following disclosure, that it would only be undesirable surplusage to enlarge further upon the same 80 initially.

With these prefacing remarks, and for a clearer conception of the improved features claimed, reference will now be had to the accompanying drawing, illustrating a practi- 85 cal embodiment thereof, in which drawing the single figure shown is a perspective as- sembled view of a sound box, its tone arm and a tone chamber, as associated with my improved throat, the latter being partly 90 broken away at its rear and one side wall, and illustrating in section, on an exaggerated scale, my invention as applied.

The numeral 5 designates generally the throat, providing the communicating con- 95 duct between the tone arm 6 and the amplifying or tone chamber 7, the said tone arm supporting and communicating with the usual sound box 8, whether of a grapho- phone, a gramophone, or other type. 100

The forward wall of the throat, which may also be conveniently designated by the numeral 5, and the rearward wall 9 thereof curve downwardly and forwardly in diver- 105 gently spaced or flaring relation, for gradu- ally increasing the volume space from the upper or inlet end to the lower or outlet end. The side walls are indicated by the numeral 10 and as a rule are very thin, while the forward and rearward walls may be and 110 generally are of comparative heavier thickness.

11 indicates a horizontal support or board disposed within the cabinet head just below

the hinged cover or dome, and this board is provided with an aperture, not shown.

The vertical branch of the tone arm 6 is disposed in communicating alignment with 5 said aperture, its lower end being supported by said board 11 and secured thereto as by the flange member 12, with suitable fastening means therefor.

The upper or inlet end of the throat 5 is 10 not positively connected directly to the vertical branch of the tone arm 6, but seats snugly up against the lower face of said board support 11 in encompassing relation with said aperture, and hence in communicating vertical registration with the vertical branch of the tone arm, as is apparent.

The lower or outlet end of the throat is somewhat analogously mounted to register with a rear or inlet opening of the tone 20 chamber 7, and the throat may be held positioned in any suitable way, illustrated conveniently by the upper and the lower guide or centering elements 13 and 14, respectively.

15 15 designates, on an exaggerated scale for clearness of illustration, a metallic resurfacing lining or coating, for the interior surfaces of the throat, which incorporates a metallic layer or leaf, of film-like thinness, 30 in the finish, and which comprises the primary essential of the present invention, although I may and generally do apply an analogous coating 16 to the exterior surfaces also, with highly beneficial results 35 especially as to the exclusion of moisture.

It might be contended that it would be a full equivalent to smoothly lay and secure a sheathing of metal over the surfaces, but it should be distinctly borne in mind that 40 such is not the case, for in that event the lining would have a limited or damped vibration with a consequent flat metallic or so-called "tin-panny" resonant quality, which would be quite as objectionable as if 45 the throat was of all-metal formation, when its freer vibrations would cause either harsh grating metallic twangs or ringing tones, largely dependent upon the resonance of the metal, and at all events any such conditions 50 would defeat the perfected acoustic properties sought for in maintaining the desired purity of tone values.

It is to be emphasized, therefore, that the 55 said lining 15 is in fact a true resurfacing agent, in that it becomes an incorporate part of the interior wooden surfaces themselves, closing the wall joinders and filling up the pores of said interior wall surfaces in the manner of a hermetic seal, and forming as it 60 were a stratified film-like metallic facing, which serves both in the capacity of a moisture and air proof reinforcing veneer as well as improving or at least maintaining constant the tone values to be emitted. Obviously the same may be said of the exterior

coating 16, excepting that the latter is not contacted by the sound waves.

This broad metallic resurfacing feature might possibly be accomplished in other equivalent ways, but in actual practice I 70 have found and demonstrated that a suitable veneering agent may simply comprise a coating of gold or aluminum leaf or their equivalent, which may be applied to either the interior wall surfaces alone, or both interiorly and exteriorly, by any of the methods usually employed in causing the adhesion of metallic leaf.

Whether or not I have exactly stated the proper reasons therefor, experimental and 80 commercial use have assuredly proven that my discovery is of superior importance, in point of preserving the purity of tone values, as has been evidenced by careful comparisons between the same machines, 85 under exactly the same conditions and translating the same identical records, excepting that in one instance the machine has been equipped with a throat as heretofore, and in the other instance with the same style of 90 throat, and even the same identical throat itself, after the film-like metallic coating has been applied in accordance with my invention. This was true also whether or not the throats had previously been treated with 95 a varnish or shellac.

While my discovery is simplicity itself, it will be nevertheless understood that I do not wish to unnecessarily restrict myself, excepting as limitations may be imposed by 100 the terms and scope of the ensuing claims, when fairly interpreted in the light of the specification and understood equivalents, and having thus made a full disclosure of 105 my invention as now practiced, what I do claim as new and patentable is:—

1. In machines of the character disclosed, the employment of a wooden throat, embodying a sound wave conducting passage, which is internally and externally resurfaced, with a suitable positively adhering metallic leaf, to provide uniformly smooth and solidly wood-backed metallic surfaces, of film-like thinness, both interiorly and exteriorly thereof.

2. In machines of the character disclosed, the combination with a sound box and tone amplifying chamber spaced therefrom, of intermediate means providing a sound wave conveying conduit, leading from said sound box to said tone amplifying chamber, which conduit includes a wooden throat that is internally resurfaced, with a suitable positively adhering metallic leaf, to provide a uniformly smooth and solidly wood-backed 110 film-like metallic lining surface for the interior thereof.

In testimony whereof, I affix my signature.

THEODORE O. LOVELAND,
